UNITED STATES PATENT OFFICE.

JOHN W. HYATT, OF NEWARK, NEW JERSEY.

BOWLING-BALL WITH SELF-CONTAINED HANDLE.

1,111,023.

Specification of Letters Patent. Patented Sept. 22, 1914.

Application filed October 24, 1913. Serial No. 797,021.

To all whom it may concern:

Be it known that I, JOHN W. HYATT, a citizen of the United States, residing at 724 Ridge street, Newark, county of Essex, and 5 State of New Jersey, have invented certain new and useful Improvements in Bowling-Balls with Self-Contained Handles, fully described and represented in the following specification and the accompanying drawings, forming a part of the same.

The object of the present invention is to furnish a bowling ball with a handle which may be drawn outward from the surface of the ball to use in throwing the same, and 15 which handle may have such proportions as to afford a firm grip for all the fingers of the hand, and may permit the fingers when throwing the ball to penetrate within its surface, so as to hold the ball close to the 20 hand.

When inserting the fingers in the ordinary finger-holes in the ball, the ball is held close to the hand and can be guided and thrown with certainty; but with handles 25 which afford a grip wholly external to the surface of the ball, the ball hangs upon the hand in an unnatural position and cannot be guided and thrown with the same certainty.

30 In the present invention, the handle is constructed so as to permit the fingers of the hand to enter a doorway in the side of the ball, and thus to hold the ball close to the palm of the hand.

35 The invention is especially applicable to a hollow ball having a spherical metallic shell, within which the fixtures may readily be arranged for supporting and operating a door for the handle in the desired manner.

40 In the present invention, the door is fitted to an oblong doorway in the surface of the ball, as wide as the hand of the user, and has a spherical exterior to match the surface of the ball.

45 The handle is drawn within the ball when rolling upon the bowling alley, and has a door-piece or door to close the doorway in the surface of the ball, and when such door-piece is drawn outwardly to grasp the 50 handle, it permits all the fingers of the hand to be inserted at one edge of the doorway and applied to a hand-piece which is fixed to the door-piece, and is especially fitted to receive all the bowler's fingers and thus 55 surely sustain the weight of the ball.

The door-piece must be movable laterally

to permit the insertion of the fingers at one edge of the doorway, and the hand-piece which remains within the surface of the ball is thus crowded laterally so as to contact 60 with such inner surface, if desired, and hang the weight of the ball directly upon the hand-piece.

A spring is provided to retract the handle, and a latch to lock it in place when drawn 65 inwardly, and two or more edges of the doorway are beveled and the edge of the door constructed to overlap such bevels, and thus sustain the door firmly upon the ball when thrown upon the floor of the alley.

If desired, lugs may be extended inwardly 70 from the ends of the hand-piece to engage inclined guide-rods within the ball, so that when the handle is drawn outwardly from the ball it is automatically moved in a lateral direction, so as to afford the space for the insertion of the hand; but such means of guiding the handle are not essential to the invention.

The invention will be understood by reference to the annexed drawing, in which—

Figure 1 is a plan of the ball looking toward the door; Fig. 2 is a vertical section on the center line of Fig. 1, showing only the means for sustaining the door when the ball is in use; Fig. 3 is a section on line 3—3 in Fig. 1; Fig. 4 is a section on line 4—4 in Fig. 3; and Fig. 5 is a view showing one side of the handle exhibiting the hand-piece which sustains the ball when throwing the same. Fig. 6 is a section on line 6—6 in Fig. 1, with the fingers applied to the handle.

The ball is shown with metallic shell *a* having a coating *b* of suitable composition, 95 as hard rubber, or other substance capable of being molded in a plastic state upon the exterior of the shell. The shell is formed in one side with an oblong doorway having ends *c* and edges *d*, *d'*, and a door *e* is fitted to move into and out of such doorway, with spherical exterior to complete the surface of the ball.

To set the surface of the door flush with the ball and to sustain any blows to which the door may be subjected when the ball is in use, beveled shoulders *c'* are formed upon the ends of the door, and the ends *c* of the doorway are correspondingly beveled, thus supporting the door rigidly when the ball is 110 in use.

A shank-plate *f* is extended inwardly from

one edge of the door, and a hand-piece in the form of a flange g is projected from the plate upon the same side as the door, and formed with hollows or notches g' adapted to receive the fingers of the hand. The plate f forms a shank upon the door-piece to move the hand-piece outward when required.

At the opposite ends of the hand-piece, lugs h are extended inwardly and formed with slotted sockets h' adapted to slide upon guide-rods i , which are held at an angle to the surface of the ball at the doorway, by shanks j threaded into bosses k within the ball at one side of the doorway.

The guide-rods slope across the doorway between the opposite sides of the ball, and their inclination is such that when the sockets h' slide upon the guide-rods it moves the doorway obliquely from one side of the doorway toward the opposite side; the slots h' in the sockets permitting the door and hand-piece to be pulled outwardly until the door can be moved laterally.

A finger-hole p is made in the shell adjacent to the edge d of the doorway, and a latch-piece r is hinged at its upper end by a screw q , in the side of the finger-hole, and pressed normally toward the plate f by a spring q' .

A notch s is formed in the plate f , with which the end of the spring-latch q engages automatically when the handle is retracted into the ball, and the door is thus held firmly flush with the surface of the ball when rolling upon the alley.

To draw the handle from the ball, a pocket f^2 is provided in the plate f just below the door-piece, adjacent to the finger-hole p ; so that a finger of one hand can be inserted in the finger-hole and operate first, to push the latch from the notch s , and second, to engage the pocket f^2 to lift the door and move it laterally sufficient to insert the fingers of the hand beneath the hand-piece and pull the handle outward. As the hand-piece remains in the shell of the ball, the fingers also lie directly within the shell, as shown in Fig. 6, and the ball is thus gripped as closely by the hand as if the fingers were inserted in the ordinary finger-sockets.

The doorway is so proportioned in practice, as well as the space between the lugs h , that all four fingers of one hand may be inserted through one side of the doorway and extended beneath the hand-piece to lie in the notches f' while supporting the ball.

The hand-piece is kept from rocking or tipping during the throwing operation, by the long slotted lugs h which are formed with shoulders h^2 to contact with the ends of the bosses k at the same time that the plate f contacts with the edge of the doorway, and the handle is thus held firmly during the throwing operation; such contact forming stops for the handle at two different points

within the ball so as to steady it securely upon the handle.

While throwing the ball, its weight may rest wholly upon the hand-piece, where contacting with the inner side of the shell, as in Fig. 6; or be sustained by the guide-rods and stops formed by the plate f and the socket-shoulders h^2 .

The handle is normally retracted by springs l attached at one end to the sockets h' , and provided at the opposite end with hook m adapted to be pulled through a hole n in the periphery of the ball, and to hook over a bridge n' adjacent such hole.

To further sustain any blows that the door may be subjected to when the ball is in use, a bracket o is projected from the interior of the ball beneath the hand-piece and fitted to contact with the same, as shown in Fig. 2, when the handle is retracted.

A dowel o' may be projected from the bracket, to engage a hole u in the hand-piece, to center the same when retracted.

It will be understood from the above description, that the handle comprises a door e connected with an inner hand-piece g , and adapted to move obliquely as it is pulled out of the ball, so as to permit the insertion of the fingers at one side of the doorway to engage them with the under side of the hand-piece, so that the ball hangs directly upon the hand while throwing it. The oblique movement is permitted by the space between the door-piece and the hand-piece, at one side of the shank or plate f .

The hand-piece g lies just within the shell when adjusted for use, and the hand of the operator thus extends partly within the shell in gripping the hand-piece, the fingers being held firmly in the notches g' in the hand-piece by the application of the thumb to the outer side of the door, as shown in Fig. 6.

The door operates not only to close the opening in the ball, but forms a rigid portion of the surface and thus resists concussions as effectively as the body itself of the ball.

The finger-hole p which is provided for the finger to release the latch r for drawing out the handle, does not impair the surface of the ball any more than the finger-holes which are often used in such balls for the insertion of the thumb and finger, and is not in practice any detriment to the operation of the ball.

The bracket o is formed, upon the side adjacent to the plate f , with a surface o^2 , parallel to the plate f when the handle is retracted, and as the spring in retracting the handle draws it toward such surface, the plate serves as an efficient guide to the movement of the handle as it enters the ball, and brings the door positively into its working position to close the doorway in the ball.

This invention affords a means of supporting the ball upon all the fingers of the hand, and thus enables many persons to enjoy bowling who have not the strength 5 in their thumb and finger to hold and throw a standard ball.

By this invention, women and persons of 10 sedentary habits may be enabled with perfect ease to support the ball, by the use of the entire hand. In the present invention, this is accomplished without impairing the rolling surface of the ball, as the handle is combined with a door which wholly closes the aperture through which the fingers are 15 inserted.

Having thus set forth the nature of the invention what is claimed herein is:

1. A bowling ball having a spherical metallic shell with a doorway in one side and 20 a handle comprising a door fitted to the doorway and having a hand-piece attached thereto, the ball having means to guide the hand-piece when moved outwardly and laterally to admit the bowler's fingers, such 25 means guiding the inner side of the hand-piece to contact with one edge of the doorway.

2. A bowling ball having a spherical metallic shell with a doorway in one side and 30 a finger-hole at one edge of the doorway, a handle comprising a door fitted to the doorway and having a hand-piece attached to its inner side, and a pocket in the handle adjacent to the door, in line with the finger 35 hole, the ball having means to guide the hand-piece when moved outwardly and laterally to admit the bowler's fingers at one edge of the doorway, a spring for retracting the handle, and a spring-latch in the 40 finger-hole arranged to engage the shank of the door, and to yield when the finger is inserted in the finger-hole to engage the pocket and draw the handle outwardly.

3. A bowling ball having a spherical metallic shell with a doorway in one side, a 45 handle having a door fitted to move into and out of such doorway and having lugs projected within the shell, inclined guide-rods within the shell extended through the lugs 50 and causing the handle to move obliquely from the doorway when drawn outward, and a spring for normally drawing the door into the doorway.

4. A bowling ball having a spherical metallic shell with a doorway in one side, a handle 55 having a door fitted to move into and out of such doorway and having lugs projected within the shell, inclined guide-rods within the shell extended through the lugs and 60 causing the door to move obliquely from the doorway when drawn outward, a spring for drawing the door into the doorway when the ball is thrown, and means for locking the door in the doorway when thus retracted.

5. A bowling ball having a spherical metal-

lic shell with an oblong doorway in one side, a door fitted to move into and out of such doorway and having lugs projected within the shell and carrying a hand-piece, inclined guide-rods within the shell extended through the lugs and causing the door to move obliquely from the doorway when drawn outward, a stop upon the handle to bear upon one edge of the doorway when the door is drawn out, and a corresponding stop for the lugs upon the guide-rod, whereby the hand-piece is supported firmly upon the ball when throwing the same.

6. A bowling ball having a spherical metallic shell with an oblong doorway in one side, 80 a door fitted to move into and out of such doorway and having lugs projected within the shell and carrying a hand-piece, inclined guide-rods within the shell extended through the lugs, the lugs being slotted to permit 85 movement of the door outward from the doorway, a stop upon the handle to bear upon one edge of the doorway when the door is drawn out, and a corresponding stop, for the lugs, upon the guide-rod. 90

7. A bowling ball having a spherical metallic shell with a doorway in one side, and a finger-hole at one edge of the same, a handle having a door fitted to move into and out of such doorway and having a shank and lugs 95 projected within the shell, inclined guide-rods within the shell extended through the lugs and causing the door to move obliquely from the doorway when drawn outward, a spring for nominally retracting the handle, 100 a spring-latch within the finger-hole adapted to engage the handle and lock it in the doorway, and to yield when the finger is inserted in the finger-hole and thus release the handle for extraction by the fingers. 105

8. In a bowling ball, the combination, with a spherical shell having an oblong doorway in one side, of a door having spherical exterior movable into and out of such doorway and having at its opposite ends lugs extended within the shell and provided with inclined sockets, a hand-piece between the lugs to be engaged by the fingers, inclined guide-rods fixed within the ball, and fitted to the lugs, and a spring for drawing the door normally into the doorway.

9. In a bowling ball, the combination, with a hollow shell having an oblong doorway for the passage of a handle and a finger-hole at one edge of the doorway for reaching the 120 under side of the door to draw the handle outwardly, of an internal guide-rod for guiding the handle, a handle having door with spherical exterior fitted to such doorway, a shank-plate extending inwardly therefrom 125 with a hand-piece at its inner edge to engage the fingers, lugs extended inwardly from the hand-piece with inclined sockets upon their ends fitted movably to the guide-rod, and a spring for retracting the handle. 130

10. In a bowling ball, the combination, with a hollow shell having an oblong doorway for the passage of a handle and two inclined guide-rods within the ball for guiding the handle, of a handle having door with spherical exterior fitted to such doorway, a shank-plate extending inwardly therefrom with a hand-piece at its inner edge to form a hand-hold, lugs extended inwardly from the hand-piece with inclined slotted sockets upon their ends, and the hand-piece shaped to contact with the interior of the shell when the handle is drawn outward, thus sustaining the ball upon the hand-piece while throwing it.
11. In a bowling ball, the combination, with a spherical shell having an oblong doorway and a door having spherical exterior

and movable into and out of such doorway, of a hand-piece, and a shank connecting the same to the door, and having at its opposite ends lugs extended within the shell, inclined guide-rods within the ball, inclined sockets upon the lugs fitted to such guide-rods, and a bracket fixed within the shell to engage the hand-piece when the surface of the door is flush with the surface of the ball, and adapted to resist the blows or concussions that may fall upon the exterior of the door.

In testimony whereof I have hereunto set my hand in the presence of two subscribing witnesses.

JOHN W. HYATT.
